INNER TUBE RADIATION WITH INTERNAL METALLIC CONDUCTION

Timothy J. Lehane and John Van Vulpén, Chicago, Ill., assignors to Vapor Car Heating Company, Inc., Chicago, Ill., a corporation of New York

Application February 14, 1942, Serial No. 430,955

8 Claims. (Cl. 257—146)

This invention relates to improvements in a steam heating system, and more particularly to improvements in a radiator for use as a part of such a system, together with means for controlling the supply of steam to such a radiator. In general, the radiator is of the type comprising an outer radiating pipe provided with a plurality of spaced radiating ribs or fins adapted to increase the radiating or heat-transmitting surface and an inner pipe or tube through which the steam is admitted at one end in a restricted or controlled manner. The opposite end of the inner tube is open while the corresponding end of the outer tube extends beyond this opening and is closed. Steam and condensate from the inner pipe will flow back through the outer pipe between the inner and outer pipes and will be discharged from an opening in the outer pipe adjacent the admission end of the inner pipe. Normally the far end of a radiator of this type, that is, the end remote from the inlet and discharge openings, will be the hotter end. This is because the steam will flow with comparatively little loss of heat through the inner pipe to the remote discharge end thereof, and the maximum heat radiation from the outer pipe will occur (particularly at first) from the remote end of this pipe in which the steam is discharged from the inner pipe.

In order to equalize this heat-transmission throughout the length of the radiator, a direct metallic contact is provided between the inner and outer pipes substantially throughout the length of these pipes so that there will be a direct conduction of heat from the inner to the outer pipe (which is discharged from the outer fins) before the steam reaches the open remote end of the inner pipe and flows directly into the outer pipe. This metallic contact may be provided for in several ways, examples of two of which are hereinafter disclosed. In addition to this there will be a direct transmission of heat from the uncondensed steam flowing from the inner to the outer pipe after the steam and other fluids leave the inner pipe and return through the outer pipe. The returning condensate between the pipes will also transfer heat from this condensate through the outer pipe, as well as forming an additional conducting material between the pipes. As a net result, the transmission of heat from all portions of the radiator throughout the length thereof will be largely equalized. Cooperating with the above, means are provided for modulating or controlling the flow of steam into the inner pipe of the radiator so that the total

heat output can be restricted as desired. Several methods of accomplishing this latter result are hereinafter disclosed.

The principal object of this invention is to provide an improved radiator and control means therefor as briefly described hereinabove and disclosed more in detail in the specifications which follow.

Another object is to provide a radiator of this improved type including means for maintaining a continuous metallic contact between the inner and outer pipes throughout the length of the radiator.

Another object is to make the two pipes non-concentric so that the pipes will be in line-engagement at one side throughout the entire length thereof.

Another object is to provide a substantially continuous metallic spacer between the pipes, throughout the length thereof, this spacer being designed so as not to interfere with the return flow of fluid between the pipes.

Other objects are to provide several alternative forms of valve or control means for restricting the flow of steam into the inner pipe of the radiator.

Other objects and advantages of the invention will be more apparent from the following detailed description of certain approved forms of apparatus designed to carry out the principles of this invention.

In the accompanying drawings:

Fig. 1 is a side elevation, partially in central vertical section, showing one approved form of radiator and associated parts.

Fig. 2 is a transverse vertical section, on a somewhat larger scale, taken substantially on the line 2—2 of Fig. 1.

Fig. 3 is a longitudinal vertical section through another form of radiator.

Fig. 4 is a transverse vertical section, similar to Fig. 2, but taken on the line 4—4 of Fig. 3.

Fig. 5 is a wiring diagram showing one means for controlling a valve of the type suggested in Fig. 1.

Fig. 6 is an elevation and longitudinal vertical section through a manually operated valve, and the adjacent end portions of the radiator such as shown in Fig. 1.

Fig. 7 is a vertical section through a temperature-modulated valve which might be substituted for the manually operated valve of Fig. 6.

Referring first more particularly to Figs. 1 and 2, steam from the source of supply will flow through pipe A into the control valve B and

thence into the inner supply pipe of the radiator indicated generally at C. Fluids discharged from the radiator will pass out through the pipe D and the steam trap E therein. Steam from pipe A will flow into the valve chamber 1 and thence through ports 2 in cage 3 past the valve 5 into and through the port 4 leading into the inner pipe 7 of the radiator C. Valve 5 is carried by stem 6 slideable through the cage 3 and this valve may be moved to closed position (in seat 4) by a spring or by an electrically operated solenoid. As indicated diagrammatically in Fig. 5 the valve is closed by spring 8 and is opened by the solenoid 9, when energized, so as to draw the core 10 thereinto against the action of spring 8. Conversely the valve could be electrically closed and opened by means of a spring.

When the valve 5 is in open position, steam will flow into and through the inner pipe 7, thence through the remote open end 11 of this pipe into the cap 12 closing the remote end of the outer pipe 13 of the radiator. The fluids entering this remote end of radiator C will flow back around pipe 7 and between the pipes into the discharge chamber 14 of the valve casing 15 and thence through port 16 into the discharge pipe D. If there is any uncondensed steam remaining in the fluids passing through discharge pipe D, the trap E will prevent the discharge of this steam. This trap comprises a bellows 17 containing a heat-responsive fluid, this bellows expanding in the presence of steam to force the valve member 18 against the seat 19 and cut off the flow of fluid through discharge pipe D, beyond the trap. In the presence of condensate and other cooler fluids, the bellows 17 will contract and open the valve 18 so as to permit these fluids to flow out through the extensions D' of the discharge pipe.

The radiator C (in the form shown in Figs. 1 and 2) comprises the inner pipe 7 and outer pipe 13, as already described, the outer end of pipe 13 being closed by the cap 12, and the inner end being seated at 20 in a port or opening at the outer end of valve casing 15.

Radiator C will normally be much longer than here indicated (the radiator being shown as centrally broken away) and the outer pipe 13 is provided with a plurality of radiating ribs or fins indicated at 21, these fins providing additional radiating surface to greatly increase the effective capacity of the radiator.

In radiators of this general type, as heretofore known, the inner and outer pipes 11 and 13 have been substantially concentric or coaxial, the steam flowing in uncondensed form (for the most part) completely through the pipe 7 and not being condensed until it has emerged into the outer pipe 13. For this reason the remote end of the radiator (that is the end adjacent the cap 12) is normally hotter, particularly at the beginning of operations and until steam in sufficient quantities has flowed back through the outer pipe toward the discharge end.

In the example shown in Figs. 1 and 2, the pipes 7 and 13 are not coaxial, but are in substantial lineal engagement throughout their length, as indicated at 22 in Fig. 2. As shown in Figs. 1 and 2, the inner pipe 7 lies within and rests upon the outer pipe 13, although a continuous metallic contact between the pipes is all that is required. As here shown, one or more spacers 23 are inserted at intervals between the pipes 7 and 13, at one side, so as to enforce and

maintain the metallic contact between the pipes at the opposite side.

It will thus be seen that there is a continuous metallic engagement between the pipes at all points throughout their length and much of the steam in inner pipe 7 will be condensed, the heat being conducted directly between the metallic members and radiated from the outer fins 21. A considerable portion of the heat from the incoming steam will thus be delivered from the radiator while the steam is flowing through the inner pipe 7 toward its remote delivery end 11. Any steam remaining in the inner pipe 7 and flowing back through the outer pipe 13 will be condensed and give up its steam in this pipe, but in the event that the flow of steam should be excessive and flow out through discharge pipe D, this flow of steam will be stopped by the trap E.

All condensate and non-condensable gases will flow back through the space between the inner and outer pipes and thence be discharged through pipe D and trap E. The greater portion of the heat remaining in the condensate will be radiated and utilized through outer pipe 13 and fins 21. This condensate flowing between pipes 7 and 13 will form an additional means to conduct heat from the steam in the inner pipe to the outer pipe 13. As a result of all of these factors the emission or transfer of heat from all parts of the radiator C will be substantially uniform throughout its length.

A modified form of radiator is indicated at C' in Figs. 3 and 4. In this construction the inner and outer pipes 7 and 13 are substantially coaxial and are separated throughout substantially their entire length by a metallic spacer 25 which may be of the general form best shown in Fig. 4 and contacting at alternate lines throughout its circumference with the inner and outer pipes, respectively. Contacting lines with the outer pipe 13 are indicated at 26, and contacts with the inner pipe 7 at 27. In this way the conduction of heat from the steam in the inner pipe to the outer pipe is provided for throughout the length of the radiator substantially as in the first described form of the invention. It will be understood that the radiator shown in Figs. 3 and 4 is supplied with steam by a valve similar to that indicated in Fig. 1, and fluids are discharged from this radiator by the same mechanisms as indicated at D and E in Fig. 1. Alternately, either of the other forms of valves shown in Figs. 6 and 7 could be used with either type of radiator C or C'.

Reference will now be made to Fig. 5 which shows a wiring diagram for a system that controls the valve B for a "cycling" operation, that is, the valve is alternately opened and closed so as to admit the steam to the radiator in "bursts" and not at a continuous stream. A pair of power supply mains are indicated at 28 and 29. At R is indicated a relay including a solenoid 30 which may be energized over the following circuit: from main 28 through wire 31, resistor 32, wire 33, terminal 34, coil 30, terminal 35, wire 36, resistor 37 and wire 38 to the main 29. When coil 30 is energized, it will pull down the core 39 against the resistance of spring 40 so as to bring the contact plate 41 into engagement with a lower pair of fixed contacts 42 and 43. When the coil 30 is de-energized, the spring 40 will pull up the stem 44, contact plate 41 and core 39 so that the plate 41 will be brought against the fixed stops 45 and 46.

The thermostat T comprises a mercury column 47 which is constantly in engagement with a

lower contact 48 and adapted to engage an upper fixed contact 49 at a predetermined temperature. This will complete a circuit through wires 50 and 51 connected between terminals 34 and 35 so as to short-circuit the relay coil 30. Thermostat T comprises an upper bulb 47^a which is exposed to the atmosphere so as to respond to atmospheric temperature changes, and also a lower bulb 47^b which is enclosed in a heating coil 52. When a current is passed through the coil 52 additional heat (for example 2 or 3°) will be added to the atmospheric temperature to cause the thermostat to function at a somewhat lower temperature than that for which it is designed.

When the contact plate 41 is drawn down by relay R so as to engage the contacts 42 and 43, a circuit will flow as follows: from main 28 through wire 53, contacts 42, 41 and 43, wire 54, solenoid coil 9, and wire 55 to the negative main 29. This will draw in the core 10 so as to open the valve 5 against the resistance of spring 8. This will permit steam to flow into the radiator C. When the relay R is de-energized and the spring 40 lifts the contact plate 41, this circuit will be broken and the coil 9 de-energized so as to permit the spring 8 to close the valve 5 and cut off the flow of steam to the radiator. When relay R is energized, a circuit will also be completed from contact 43 through wire 56, resistor 57, and wire 58 to and through the heating coil 52 and thence through wire 59 to the negative main 29.

Assuming first that the prevailing temperature is such that the valve 5 is open and steam is being supplied to the radiator C. At such time the auxiliary heater 52 will also be functioning and the circuit through thermostat T will close so as to short-circuit or de-energize the relay R. As a consequence the spring 40 will raise the plate 41 and break the valve-operating circuit permitting the valve 5 to close. The heater 52 will also be de-energized when the contact 41 is raised out of contact with contact 43. As a consequence the mercury in thermostat T will fall and break engagement with the fixed contact 49 so as to open the circuit through this thermostat and relay R will no longer be short-circuited. The relay will again close the contact 41, thus re-opening the valve 5 and causing the heater 52 to function and add heat to the thermostat T, which will rise until upper contact 49 is engaged and the cycle of events will again be repeated. As a consequence steam will be admitted to the radiator in successive bursts instead of as a continuous flow. This will restrict or modulate the supply of steam to the radiator and when the desired atmospheric temperature is attained the circuit through thermostat T will remain closed, the relay R will remain de-energized and the valve 5 will remain closed so as to no longer admit steam to the radiator.

In lieu of the electrically operated valve just described, a manually operated valve B', as shown in Fig. 6, could be used. This valve B' comprises a movable valve member 60 adapted to close against the valve seat 61 at the upper end of the port through which steam enters from supply pipe A. The hand wheel 62 adjusts the vertical position of the valve 60 through a screw mechanism, as is usual in valves of this type. By modulating the lifted position of this valve the flow of steam is adjusted or modulated, this steam flowing through pipe 63 and connection 64 into the chamber 65 in a fitting 66. The steam flows from chamber 65 through pipe section 67 into

the inlet end of inner pipe 1 of the radiator. The outer radiator pipe 13 discharges into the chamber 68 of fitting 66 and from thence into the discharge pipe D, as already described.

6 A second form of temperature controlled valve B' (see Fig. 7) could be substituted for the valve B' of Fig. 6. This valve comprises a movable valve member 69 adapted to adjustably cooperate with the steam port 70 in controlling the flow of steam through the valve casing 71. The movable valve member 69 is connected through the stem member 72 with a base-plate or end member 73 engaging within the lower surface of an inverted cup member 74 which forms the bottom of a flexible bellows member 75 supported at its other end within the fixed standard 76. A thermostatic bulb 77, containing a volume of heat-responsive fluid is positioned at any desired locality so as to respond to the temperature at that point and is connected through the flexible pipe 78 through fitting 79 with the upper portion of the space within the bellows member 75. When heated, the fluids within these members will expand so as to expand the bellows 75 and force down the stem 72 and valve member 69 toward closed position. The spring 80 confined between the member 73 and an adjusting nut 81 threaded on the tubular guide member 82 is adapted to lift or open the valve member 69. By suitably 20 adjusting the manually operated nut 81 the compression of spring 80 may be adjusted and thus determine the temperature at which the valve 69 will be operated. The flow of steam through the valve B' can thus be made to respond to temperature changes at any location.

We claim:

1. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes.
- 40 2. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes.
- 45 3. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 50 4. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 55 5. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 60 6. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 65 7. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 70 8. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.
- 75 9. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe being closed and enclosing the open end of the inner pipe, and means separate from the pipes for maintaining a constant heat-transmitting metallic connection from the inner pipe to the outer pipe throughout substantially the entire length of both pipes without preventing the return flow of fluids between the pipes.

of both pipes, and spacing means positioned between certain of the other portions of the pipes to maintain them in contact with each other.

4. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe enclosing the open end of the inner pipe, the inner pipe resting upon the bottom inner surface of the outer pipe so as to be in metallic contact therewith throughout substantially the entire length of both pipes, and spacing means positioned between certain of the other portions of the pipes to maintain them in said metallic contact with each other.

5. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe enclosing the open end of the inner pipe, the inner pipe resting upon the bottom inner surface of the outer pipe so as to be in metallic contact therewith throughout substantially the entire length of both pipes, and spacing means positioned between certain of the other portions of the pipes so as not to interfere with the return flow of fluids between the pipes.

6. In a heating system, a radiator comprising an inner feed pipe, an outer radiating pipe en-

closing the inner pipe, a plurality of radiating fins on the outer pipe, means for feeding steam into one end of the inner pipe, means for discharging fluids from the corresponding end portion of the outer pipe, the other end of the outer pipe enclosing the open end of the inner pipe, and metallic spacing means in heat-transmitting contact with both pipes and maintaining them in heat-transmitting contact with each other throughout substantially their entire length.

5. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe enclosing the open end of the inner pipe, and metallic spacing means in heat-transmitting contact with both pipes throughout substantially the entire length thereof.

25 7. In a heating system, a radiator comprising an inner feed pipe, an outer radiating pipe enclosing the inner pipe, a plurality of radiating fins on the outer pipe, means for feeding steam into one end of the inner pipe, means for discharging fluids from the corresponding end portion of the outer pipe, the other end of the outer pipe enclosing the open end of the inner pipe, and metallic spacing means in heat-transmitting contact with both pipes throughout substantially the entire length thereof without preventing the return flow of fluids between the pipes.
